THOMAS E. CLARK AND JAMES E. CLARK, OF DETROIT, MICHIGAN, ASSIGNEES TO CONTINUOUS TRAIN CONTROL CORPORATION, OF DETROIT, MICHIGAN, A CORPORATION OF MICHIGAN

TRAIN-CONTROL SYSTEM

Application filed March 15, 1926. Serial No. 94,754.

This invention relates to the control of railway trains by means of one or another high frequency current propagated in the rails of tracks which are divided into blocks,

5 a current propagating device being connected to the rails of each block, preferably to the exit end thereof, and each propagating device comprising means influenced by the current in the block in advance of that to 10 which such device propagates current, for the purpose of controlling such propagation to accord with the traffic conditions in a selected number of blocks in advance, and its object is to provide a wayside circuit extending 15 along the trackway of the block from such propagating device, and a series of transformers connected to said conductors and to the rails so that the propagated current may be impressed upon the rails of the 20 block with sufficient uniformity throughout the length of the block.

A further object of this invention is to provide resonant circuits on a locomotive or other power vehicle, embodying vacuum 25 tubes and collector coils connected thereto and adapted to pick up electro-magnetic force from the charged rails which shall so affect the tubes that the plate currents therefrom shall govern the operation of a polar 30 neutral relay; to provide an electro-pneumatic valve to control the operation of air brakes and circuits between a current source and the valve controlled by said polar neutral relay; to provide a governor in said circuit 35 so that when the speed of the vehicle exceeds the speed which is predetermined for the condition under which the particular current present in the rails is propagated, the effective circuit between the current source and the valve will be opened; and to provide manually operable means for establishing a circuit 40 between the current source and the valve which shall remain closed while the vehicle proceeds not above at a predetermined minimum speed.

This invention consists in the novel combination of the instrumentalities shown diagrammatically in the accompanying drawings and particularly pointed out in the 45 claims.

In the drawings Figs. 1 and 3 are diagrams of the train control system embodying the present invention. Fig. 2 is a perspective of a transformer.

Fig. 4 is a diagram of mechanism for operating a switch from a semaphore. 55

Similar reference characters refer to like parts throughout the several views.

The rails 1 and 2 are shown divided into blocks A, B, and C by means of insulations 60 3 in the usual manner and a track installation is connected to the exit ends of blocks A and B. The track and locomotive installations embody relays whose armatures are indicated by small letters which will be used 65 with the designating characters of the relays.

Alternating current is supplied to the two line wires 5 and 6 from any current source such as a generator G, and each track installation embodies a wire 7, over which current 70 normally flows through primary winding 8 of the main transformer, wire 9, armature *a* of a high-resistance polar-neutral relay 10, wire 12, armature *a* of relay 13 and wire 14. Each relay 10 is controlled by the current in 75 the track rails of the block ahead and has three conditions, positively or negatively energized and de-energized. When it is either positively or negatively energized, it attracts its armatures *a* and *b* and thus closes the circuit to the primary winding 8, but when it is de-energized, which occurs when its block of track is occupied, the circuit to the primary winding is opened and the adjacent track installation for the next block in the rear is 80 inoperative. 85

The vacuum tubes 15 and 16 are the generators of the control currents and their filaments receive current from the portion 17 of the secondary winding of the main transformer, the current passing over wires 18 and 19, variable resistance 20 and wire 21 to the filament of tube 15 and back over wires 23 and 24 to winding 17. Current also passes over wire 18, adjustable resistance 25 and 90 wire 26 to the filament of tube 16 and back over wire 24. 95

The secondary winding of the main transformer for the plate current of tube 15 consists of the parts 17 and 27, while that for 100

the tube 16 consists of the parts 17, 27 and 28. The plate circuit of the tube 15 during the positive portion of the cycle of the current in wires 5 and 6, is over wire 23, coils 17 and 27, wire 32, coil 31 and wire 30 to the plate, while the circuit during the negative portion is over the wire 30, coil 31, wire 32, condenser 38, wires 18 and 19, resistance 20 and wire 21. This circuit carries a pulsating current of high-frequency and causes a pulsating charge in the grid circuit of this tube 15, said circuit consisting of the wires 23, 24 and 41, inductance coil 42, wire 43, extending therefrom to the grid leak 44 and condenser 45, and wire 46.

The coil 42 being the secondary of a transformer of which the coil 31 is the primary, a pulsating charge is impressed upon the grid circuit and negative potential is charged on and discharged from the grid of tube 15, the condenser 45 and grid leak 44 preventing positive potential in the grid. This charge and discharge is probably both the cause and effect of the pulsations in the plate circuit and coil 31. The rate of vibrations and the wave lengths of the currents are controlled by the adjustable condenser 47 which shunts the coil 31.

The plate current of tube 16 flows in one direction from coils 27 and 28, over wire 36, inductance coil 35 and wire 34, and in the opposite direction from the plate over wire 34, coil 35, wire 36, condenser 39, wire 18 and adjustable resistance 25 to the filament of tube 16, the condenser 39 serving as a low resistance path for radio-frequency oscillations to by-pass the windings 27 and 28. The plate current, therefore, never flows in the opposite direction through the coils 27 and 28 of the main transformer. The adjustable condenser 37 tunes the plate circuit of tube 16 in resonance with the plate circuit of the other tube.

The grid of tube 16 is controlled by the inductance coil 31 of tube 15 acting on the inductance coil 48 which connects to the wire 24 by the wire 49 and to the grid leak 50 and condenser 51 by the wire 52. The wire 53 connects the grid of tube 16 to its leak and condenser. As the charge in this grid pulsates in unison with the charge in the grid of and with the current in the plate circuit of tube 15, the plate current of tube 16 also pulsates in such unison.

The reason for using two tubes is as follows. The track circuit comprising the rails between the wires 66 and 68 and the nearest wires 71 and 72 is lengthened and shortened by the trains passing over this portion of the block to which the installation is connected. This change in length of circuit would normally change the wave length of the current flowing in the plate circuit through the reaction between the inductance coils 60 and 59 and coils 57 and 35 which are inductively

connected. But the frequency of the pulsations of the current in this plate circuit is controlled by the current in the grid circuit which includes the coil 48 which current always pulsates in unison with the current in the plate circuit of tube 15 which is unaffected by any change in the track circuit. The rate of vibrations and wave lengths are therefore controlled by the tube 15 and its circuits. This tube may be of very much less capacity than the tube 16.

In the operations of train control systems employing the track installations above described, great difficulties were met with because the current in the rails dissipated from the input end of the block, which is usually the exit end, toward the entrance end and the mechanism which embodies the present invention has been devised to overcome these difficulties and to insure a substantially constant current of sufficient strength throughout the block. Much of the success of the present invention arose from the proper installation of the transformer shown in Fig. 2, which is admirably adapted for currents of radio frequency.

The transformer (Fig. 2) is in the form of a rectangle and is built up of thin sheets of steel 58 coated with an insulating varnish, preferably by dipping. A winding is on each core, the primary winding 59 being of finer wire and the secondary winding 60 of heavier wire and of fewer turns so that the output thereof will be of lower voltage but of higher amperage.

The fixed output inductance 57 co-acts with the inductance coil 35 of the plate circuit of the tube 16, and this output inductance is a portion of an oscillating circuit which is from the coil 57 over condenser 62, wires 55 and 63 to primary winding 59. Only a part of the current passes over the wire 63, and the remaining portion of the current passes over the wire 55 to the other transformers positioned along the trackway. From the first primary 59 the current passes over wires 64 and 56 to the output coil 57.

The secondary winding 60 of the first transformer connects to the rails by means of wires 66 and 67 and wires 68 and 69 respectively, a condenser 70 being inserted to prevent passage of battery currents. The primary windings 59 of the other transformers, which may be of any desired number, connect to the wires 55 and 56 and the secondary windings connect to the rails 1 and 2 by means of wires 71 and 72 respectively, condensers 70 being again inserted in one of these wires.

The transformers may be adjusted so that the current at all points along the rails will be substantially uniform by so connecting the wires 71 and 72 to the secondary windings 60 of the transformers that proper current output of these windings will be secured by selecting the proper lengths of such windings.

As the transformer next adjacent the axle T, in any block is most active, the current in the rails at the entrance end of a block when the axle T is at that end will be of sufficient strength to properly influence the instrumentalities on the locomotive.

In the drawings we assume that the track in advance of block C is unoccupied for two or more blocks, and the high resistance polar neutral relay of block C is energized, holding up its armatures *a* and *b*. The control current of the track battery of block C (not shown) passes rearwardly along rail C¹, wire 74, relay 10, wire 75 and rail 2 back to said battery. This so energizes relay 10 at station B that its armatures *c* and *d* are swung clockwise. At each track station, that is, at the exit end of each block and at the entrance end of the block in advance is a semaphore of well known design.

These semaphores are therefore shown diagrammatically and embody the signal arms 65 which assume the solid line position, as shown in Fig. 1 when positive current is received by the relay 10, assume the dotted line position of Fig. 1 when negative current is received by relay 10, and assume the position shown in Fig. 3 when no current is received by relay 10. These signal arms are operated by current from the station battery 76, and when the armature 10^a is swung clockwise, by reason of positive current received by relay 10, current flows over wire 77, armature 10^b, wire 78 to the signal post and over wire 79 back to the battery. This causes the signal arm 65 to assume the intermediate or dotted line (Fig. 1) or "caution" position. Current also flows from wire 78 over armature 10^a and wire 80 to the signal post causing the signal arm to move one step farther to the solid line position (Fig. 1) or "clear" position. If negative current is received by relay 10, its armatures *c* and *d* swing counter-clockwise and current flows only over wire 78 to the signal post and arm 65 assumes its intermediate position. If no current flows from battery 76, as in Fig. 3, the signal arm assumes the "danger" position.

Positive current in relay 10 also causes its armature *c* to swing clockwise, closing the circuit to relay 81 over wire 77, armature 10^b, wire 78 and armature 10^c, this relay being connected to the return wire 79. Energized relay 81 attracts its armatures *a* and *b* and closes the circuit consisting of the wire 82, armature 81^b, wire 82^a, condenser 83 and wire 84 between the wires 30 and 32, thus shunting the condenser 83 into the circuit of the plate coil 31 of tube 15, and closes the circuit consisting of wire 85, condenser 86 and wire 87 between the wires 34 and 36 of the circuit of the plate coil 35 of tube 16, resulting in an increase of wave length of the current propagated in the rails by the output coil 57. Thus the wave length of the

current for "clear" conditions may be 30,000 meters while that for "caution" conditions may be 25,000 meters. When the relay 10 receives negative current, the relays 10^c and 10^a are swung counter-clockwise and the relay 81 is de-energized and the caution current is propagated by tube 16.

When the block in advance is occupied, as in block B, relay 10 of station A receives no current and its armatures *a* and *b* fall, opening the circuit of the main transformer so that no current is propagated in the rails of block A.

Each track battery 89 connects to a two-way switch having arms 90 and 91, one under clear conditions connecting to the wire 67 and to rail 2 and the other connecting to rail 1 by wire 92, relay 13 and wire 69. The switch arms are connected to the adjacent semaphore arm, so that when the signal arm 65 is in solid line position (Fig. 1) the switch is in solid line position so that positive current flows to rail 1. While any desired means may be employed to connect the switch arms 90 and 91 to the semaphore 65, that shown in Fig. 4 may be found useful. A small arm 170 is attached to the shaft of the semaphore and swings with it. A cable 171 connected to the end of this arm attaches to the bar 172 of insulating material connecting the arms 90 and 91. A spring 173 may be used to pull down the arms 90 and 91. The range of movement of the arm 170 is from 22½ degrees on one side of the perpendicular to 67½ degrees on the other, the switch arms being wide enough to keep contact while the arm 170 crosses the perpendicular. When the signal arm swings to "caution" position, the switch arms remain in this position and positive current still flows to rail 1. The switch arms swing counter-clockwise when the signal arm moves to "danger" position. With block B occupied, relay 10 adjacent the track installation A in the rear receives no current, battery B⁸⁹ being short circuited by axle T and the signal arm at said next station in the rear assumes the "danger" position. The relays 13 are never energized unless an axle T closes their circuits.

The train control installation of a block, therefore, is inoperative unless the block is occupied, at which time the relay 10 at the entrance end of the block is de-energized. These track installations propagate substantially uniform electro-magnetic waves in the rails throughout the lengths of the blocks, the wave lengths or absence of current being automatically determined by the occupancy of the track ahead, and such propagation taking place only in occupied blocks, thus saving current and insuring maximum life of the tubes.

The locomotive installation shown in the drawings makes use of the generator 99 which normally supplies current for the locomotive

headlight, and this generator supplies current to the rotary generator or dynamotor D over wires 100, 101 and 102, the return being over the wires 103, 104 and 105. This generator current is preferably of about 32 volts.

The locomotive installation embodies two vacuum tubes 106 and 107, the current for the filaments of these being supplied by the generator 99 over wires 100 and 101, resistance 108 and wire 109 to the filament of tube 107, wires 111 and 112 to the filament of tube 106 and return wires 113 and 105 back to the generator.

15 Mounted on the locomotive, adjacent to but spaced from the rails, are two collector coils 114 and 115, the former connecting to the filament of tube 106 by wires 111 and 112, and to the grid of this tube by the wire 116, grid leak 117 and condenser 118, an adjustable condenser 119 being in shunt between the wires 112 and 116 to tune this circuit to the wave length of one of the currents propagated in the rails, preferably to the "clear" current. The other coil, 115, connects to the filament of tube 107 by the wire 109 and to the grid of this tube by the wire 120, grid leak 121 and condenser 122, an adjustable condenser 123 between the wires 109 and 120 being adapted to tune this circuit to the wave length of the other current propagated in the rails, preferably to the "caution" current.

15 The plate currents for each of these tubes is produced by the dynamotor D and is preferably of about 200 volts. When either of the collector coils picks up current, a negative potential charge accumulates on the grid element to which the coil is connected. This obstructs the normal action of the tube and few electrons pass to the plate from the filament. When neither coil receives current, high voltage current flows from the dynamotor D over wire 125, relay 126, wire 127, windings 128 and 129 of a polar neutral relay, and wires 130 and 131 to the plates of the two tubes, the return being over the filament of tube 106, wire 112, filament of tube 107 and wires 109, 101, 102 and 132. This causes relay 126 to attract its armature *a* to close the circuit to the red lamp R in the cab, the circuit being over wire 100, resistance 134, lamp R, wire 135, armature 126^a and wires 104 and 105.

15 The windings 128 and 129 neutralize each other when both receive current, but both are necessary to carry sufficient current to energize the relay 126 sufficiently for it to pick up its armature. If either of the windings 128-129 receives current, the relay will pick up the armatures *a* and *b*. If coil 114 picks up current, relay 128 receives no current and the polar armatures *c* and *d* will swing clockwise, but when coil 115 picks up current, these armatures will swing counter-clockwise.

15 We have indicated a speed governor 138

having arms 139 and 140 which normally close the circuits between common wire 141 and the wires 142 and 143 respectively. This governor is attached to an axle of the locomotive and when the speed of the locomotive exceeds that permitted for "danger" conditions, say ten miles per hour, the arm 139 swings out and opens the circuit between the wires 141 and 142. When the speed exceeds that for "caution" conditions, the arm 140 opens the circuit between the wires 141 and 143.

In the present system we employ an electro-pneumatic train control valve 145 which embodies a normally energized solenoid, 80 which valve connects to the air brake system by a pipe 146, and, when open, permits the pressure in this system to escape by a vent 147, which escape occurs when the solenoid 145 is de-energized.

85 Referring now to Fig. 1, the positions of the parts indicate reception of current by collector coil 114. Winding 128 receives no current so that winding 129 holds up armatures *a* and *b* and swings armatures *c* and *d* 90 clockwise. Current from the generator 99 flows over wire 100, resistance 134, wire 150, green lamp G., wire 151, armature 129^a, wire 152, armature 129^b and wire 105 back to the generator. This green lamp indicates clear 95 conditions.

90 Current also flows over wire 100, fore-stalling key 153, wire 154, electro-pneumatic valve 145, wire 155, armature 129^c, wires 156 and 152, armature 129^b and wire 105 to the 100 generator. The valve 145 will therefore remain closed so long as "clear" current is picked up by coil 114.

95 When "caution" current is picked up by collector coil 115, winding 128 becomes energized and its armatures *c* and *d* swing counter-clockwise, as indicated by dotted lines in Fig. 1. Current now flows from the generator to yellow lamp Y and thence over wire 157, armature 128^a, wire 152, armature 110 129^b and wire 105 back to the generator.

105 If the locomotive is running at less than "caution" speed, current flows from generator 99 to the valve 145 via forestalling switch 153 and over wires 155 and 141, governor arm 140, wire 143, armature 128^c, wires 156 and 152, armature 128^b and wire 105 to the generator. But if the speed is greater than that predetermined for "caution" conditions, the arm 140 swings out to open this circuit and the de-energized valve 145 opens and the brakes will then reduce the speed to that thus determined.

115 When no current is picked up by the collector coils, both windings 128 and 129 become equally energized and neutralize each other, their armatures *a* and *b* dropping and opening the circuit to the valve 145 which would normally cause the application of the brakes. But this application is not instan-

taneous because of the large volume of air in the train pipe and the small size of the vent 147. If, therefore, the engineer depresses his forestalling key 153 as soon as 5 current passes to the red lamp R, he establishes a circuit over wires 101, 160, relay 161, wire 162, switch 163, key 153 and wires 164 and 105. Armatures *a* and *b* of relay 161 being picked up, a holding circuit for this 10 relay is closed over wires 100, 101, 160, relay 161, wire 162, armature 161^a and wires 165 and 105. The key is now released and returns to normal position.

A circuit for valve 145 is also established 15 consisting of wire 100, key 153 and wire 154 to the valve and wires 155, and 141, governor arm 139, wire 142, armature 161^b and wires 165 and 105 to generator 99. This circuit is opened immediately the locomotive exceeds 20 its "danger" speed, but this circuit permits the locomotive to move forward to the place where an obstruction has caused the "danger" conditions of the track station next ahead.

Relay 161 remains energized until the current which energizes it is given a path of lower resistance by the armature 128 when attracted, which armature connects the wires 160 and 105 when either of the windings 128 and 129 is energized because of current 25 picked up from the rails by either of the receptor coils. A resistance 166 in the wire 160 prevents the generator 99 being short circuited by the last named circuit.

The switch 163 remains in normal position 30 until the blast of air from the vent 147 reaches a predetermined volume, which occurs when the valve 145 has been open a predetermined length of time, say five seconds, so that, should the engineer fail to depress 35 his forestalling key within that time, the brakes will be applied. The construction and operation of the valve 145 and of the switch 163 are fully set forth in our previous Patent No. 1,697,949 dated Jan. 8th, 1929.

40 The details of constructing the arrangements of the circuits and the ratios of the wave lengths may all be changed by those skilled in the art without departing from the spirit of our invention as set forth in the following claims.

50 We claim:—

1. In an automatic brake system for railway vehicles on track rails carrying radio-frequency currents whose wave lengths depend upon the occupancy of the track ahead, the combination of a plurality of receiving circuits, each tuned to resonance with one of the currents in the rails, an electro-pneumatic valve to control the brake system on 55 the vehicle, a current source and a plurality of circuits between it and said valve, whereby current from said source may be conducted to said valve to hold it closed, electro-magnetic means for opening and closing said circuits, a plurality of conductors between said

current source and said electro-magnetic means, said electro-magnetic means opening said plurality of circuits to said valve when current is received over both said conductors and opening one or the other of said circuits to said valve when receiving current over but one of said conductors, and electron tubes in said conductors and controlled by the currents in said tuned receiving circuits to control the flow of current in said conductors to 70 said electro-magnetic means. 75

2. In an automatic brake system for railway vehicles on track rails carrying radio-frequency currents whose wave lengths and presence depend upon the occupancy of the track ahead, the combination of a plurality of receiving circuits, each tuned to resonance with one of the currents in the rails, an electro-pneumatic valve to control the brake system of the vehicle, a current source and a plurality of circuits between it and said valve whereby current from said source may be conducted to said valve to hold it closed, electro-magnetic means for opening and closing said circuits, a plurality of conductors between the current source and said electro-magnetic means, said electro-magnetic means opening said circuits when current is received over both of said receiving circuits or when no current is received and opening one of said circuits to said valve when current is received over but one of said receiving circuits, and electron tubes in 80 said conductors and controlled by current in said receiving circuits to control the flow of current in said conductors to said electro-magnetic means. 85

3. In a construction as described in claim 2, the combination of a speed governor connected into the circuits between the electro-magnetic means and the valve to open and close said circuits according to the speed of the vehicle. 95

4. In a construction as set forth in claim 1, the combination of a normally open additional circuit between the current source and the valve, and a manually operable key adapted to close said last named circuit so as to permit the vehicle to proceed when no current is received over the receiving circuits. 100 105 110 115
